THERMALLY RESPONSIVE SWITCH

Charles Grinshaw, Fulton, Ill., assignor to General Electric Company, a corporation of New York

Filed June 3, 1960, Ser. No. 33,817

3 Claims. (Cl. 200—113)

This invention relates to thermally responsive switches, and more particularly, thermally responsive overload switches of the automatically resetting type.

Thermally responsive overload switches are frequently used to provide thermal protection for electrical apparatus, such as electric motors. One form of such a switch incorporates a bimetallic element carrying the movable contact, and a stationary contact which cooperates with the movable contact to control the circuit of the apparatus to be protected. The bimetallic element and the stationary contact of such a switch may be serially connected in the circuit to be protected, and the switch may be made responsive to both the ambient temperature and overload current. In order to provide an efficient protective switch for an electric motor, it is often advantageous to mount such a switch in a relatively small area, such as directly within or between the windings of the motor, so that the switch will respond directly to the ambient temperature of the windings. For this application, it is desirable that such a switch have a housing of high thermal conductivity and of extremely low thermal mass, and also that it substantially reduce the amount of internal heating for the switch so that it will provide an efficient temperature response under overload conditions. It is further desirable that such a switch be small in size, compact and simple, easy to assemble, and relatively inexpensive.

An object of this invention is to provide an improved thermally responsive switch which is novel in construction and which due to its relative simplicity may be manufactured at a reduced cost.

Another object of this invention is to provide a new and improved thermally responsive switch which includes a novel switch housing of extremely thin or flat over-all configuration and has an extremely low thermal mass, with high thermal conductivity.

A further object of this invention is to provide a new and improved thermally responsive switch of wafer-like configuration which may be conveniently mounted in relatively small positions in an electrical apparatus for efficiently sensing ambient temperature and providing overload protection.

In carrying out my invention, in one form thereof, I apply it to a thermally responsive switch having a pair of contacts and a thermally responsive bimetallic member. The switch housing is formed by the cooperation of a pair of thin conductive strips at least one of which is recessed. The bimetallic member is attached to one of these conductive strips and its free end carries a movable contact. A fixed contact which mates with the movable contact is attached to the inner surface of the other strip. Each of the recessed strips has a terminal portion integral to it. Between the two strips, an insulating spacer is interposed to electrically separate the strips from each other. The strips are then sandwiched together about the insulating spacer to form a wafer-thin switch of low thermal mass, and a very low internal heating characteristic. Such a switch provides an efficient temperature response under load conditions.

Further aspects of my invention will become apparent hereinafter, and the specification concludes with claims particularly pointing out and distinctly claiming the subject matter which I regard as my invention. The invention, however, as to organization and method of operation, together with further objects and advantages thereof, may best be understood by reference to the following descrip-

2

tion when taken in conjunction with the accompanying drawings, in which:

FIG. 1 is an elevational view of a thermally responsive switch embodying my invention;

5 FIG. 2 is a plan view of the switch of FIG. 1, with a portion of the upper strip of the switch housing broken away to show part of the bimetal and the movable contact which it carries;

10 FIG. 3 is a sectional view taken substantially along the line A—A of FIG. 2;

FIG. 4 is a sectional view taken substantially along the line B—B of FIG. 1, with the insulating spacer represented by dotted lines;

15 FIG. 5 is a perspective view of the switch of FIG. 1, partially exploded to show interior details;

FIG. 6 is a perspective view of the switch of FIG. 1; and

20 FIG. 7 is a schematic sectional view of a portion of a motor incorporating the thermally responsive switch of the present invention.

25 Referring now to the drawings, and more particularly to FIGS. 3 and 5, I have shown a thermally responsive switch 1 which consists of only a few basic parts, and includes an upper conductive sub-assembly, a lower conductive sub-assembly, and an intermediate insulating spacer means.

30 To substantially reduce the thickness of switch 1 and give it a diminutive, and wafer-like or pill-shaped over-all appearance, housing 3 of my switch 1 has been made from a pair of thin recessed metallic strips 5 and 7. One of these strips, such as upper strip 5, has a recessed portion or cavity 9 for receiving the bimetallic movable arm 11 of the switch. (See FIG. 3.) A stepped surface section 13 is formed in one side of the peripheral flange 35 surrounding the cavity 9 (as shown in FIG. 5), and support 15 for the bimetallic contact arm 11 is fastened to this section 13 by welding. For connecting strip 5 to the bared end of a conductor lead, outwardly extending tab 17 has been formed thereon. Tab 17 may be crimped and welded (as seen in FIG. 2) to one or more of the conductor leads of the control circuit for an electrical apparatus such as a motor which is to be protected from thermal overload. Tab 17 thus serves as an integral external terminal for conductive strip 5 so that an effective terminal area of low electrical resistance is thereby obtained. The thin thermally conductive area of strip 5 also provides a low thermal mass for sensing ambient temperatures of an external apparatus.

35 Turning now to the thermally responsive means affixed to strip 5, this comprises the bimetallic contact arm illustrated at 11. The construction and arrangement of the particular arm 11 illustrated herein, together with the method of manufacturing it, is the invention of John L. Slonberger, and this construction and arrangement are described in detail and claimed in his copending application Serial No. 11,718, filed on February 29, 1960, and assigned to the same assignee as the present invention. Bimetallic arm 11 (as shown in FIG. 4) is essentially a split annular disc of bimetallic material. This bimetal disc includes a pair of arcuate arms 23 with their free ends 21 separated by a radially extending gap or split. The disc or arm 11 is attached to support 15, as shown in FIGS. 4 and 5, by welding a base portion of the disc (opposite to the free ends thereof) to an intermediate section of the support 15 so that the free ends of the bimetal are suspended from the support in cantilever fashion. The free ends of the bimetal are then drawn toward each other to reduce the gap the desired amount and the disc is stressed into a dished formation. Contact button 19 is then welded to the free ends of the bimetal to retain them in their drawn position, and the size of the gap between the free ends of the bimetal determines the

temperature differential of the bimetal. The contact weld is coplanar with the bimetal disc and this welded contact makes it easier to adjust the bimetal subsequently to the desired level of temperature response. By welding the contact button to the split ends 21 of the bimetal, the desired snap action for the bimetal disc and an integrally affixed movable switch contact and blade assembly thus are concurrently obtained.

As seen in FIG. 5, upper strip 5 of my switch 1 thus has the thermally responsive snap acting bimetal arm 11 mounted upon it by means of support 15, so that an electric current path of low electrical resistance and very low thermal mass is provided from tab terminal 17 to the contact button 19 through the thermally and electrically conductive strip 5, the support 15, and bimetal 11. All of these aforementioned elements which are attached to upper strip 5 make up the upper strip sub-assembly, as shown in FIG. 5.

Turning now to the lower conductive sub-assembly of my switch 1, as shown at the bottom of FIG. 5, lower strip 7 is somewhat similar in overall appearance to upper strip 5, and is both thermally and electrically conductive. Strip 7 includes recessed portion 25 which has essentially the same area as recess 9, and it also has an outwardly extending tab 27 for crimping and welding one or more other control circuit conductor leads thereto for connection to the other side of the control circuit. (See FIG. 2). Fixed contact button 33 is welded to the inner surface of recess 25. Button 33 extends upwardly from the inner surface of strip 7 (as shown in FIG. 5) to mate with movable contact button 19 upon flexure of bimetallic arm 11 to its contacts closed position.

As seen in FIG. 5, lower strip 7 thus comprises an electrically conductive path between terminal tab 27 thereof and fixed contact button 33 through strip 7. These elements make up the lower conductive sub-assembly, and this sub-assembly also has a low electrical resistance and a very low thermal mass.

The upper and lower conductive sub-assemblies are fastened together in a simple and efficient manner to form my switch 1. For this purpose, strip 7 has a plurality of longitudinally spaced peripheral tabs 29 integral thereto. To electrically insulate the conductive paths formed by the upper and lower conductive sub-assemblies of which strips 5 and 7 are a part, I have provided a specially constructed slotted insulating spacer 31. (See FIG. 5.) The periphery of this spacer extends beyond the oppositely disposed outer edges of strips 5 and 7 (as shown by FIGS. 4 and 6), and it also has extensions or flaps 31a and 31c which protrude further outwardly adjacent tabs 29. To fasten the two sub-assemblies together, the thin spacer 31 is first interposed between them in the manner suggested by FIG. 4. The tabs 29 of strip 7 are then bent over and against the upper surface of the peripheral flange 35 which surrounds recess 9 of strip 5, to securely fasten the two strips together. Spacer 31 is thus positioned in sandwich-like fashion between the two mating strips of switch housing 3. The flaps 31a and 31c of spacer 31 adjacent tabs 29 are wrapped around the flange 35 of strip 5 with the tabs and held firmly against the flange 35 underneath the tabs (as shown in FIG. 6) to assure the proper insulation between the strips.

To conveniently calibrate my assembled switch 1 for the desired trip temperature, or the temperature at which the bimetallic movable contact arm 11 snaps open, I have provided calibration screw 37. Screw 37 has a small outwardly convex head portion, and a shank portion 41 which is in threaded engagement with a tapped hole 43 in strip 5. Hole 43 overlies cantilevered extension 15a of bimetal support 15. As screw 37 is tightened, its threaded engagement with tapped hole 43 of strip 5 forces it inwardly into the recessed portion 9 of the housing 3 to thus deflect extension 15a of support 15 downwardly (as shown in FIG. 3). As extension 15a deflects into the recess and toward strip 7, this decreases the pressure ap-

plied by the snap acting bimetal arm 11 following engagement of movable contact button 19 with fixed contact button 33 and thus lowers the tripping temperature. Conversely, by loosening or unscrewing the calibration screw 37 from its tapped hole, extension 15a is deflected away from strip 7 to increase the contact pressure and raise the tripping temperature of the switch.

To insure against the possibility of extension 15a of the bimetal support engaging the bottom of strip 7 and thus short circuiting the switch contacts, spacer 31 has an inner extension 31b which lies directly between extension 15a and strip 7 to provide insulation therebetween. (See FIGS. 4 and 5.)

In order to reduce the over-all dimensions of my switch 1 and thus enhance its versatility, the upper and lower strips 5 and 7 are each stamped from a relatively thin sheet of metallic material, such as sheet steel having a thickness of .025 inch. The depth of the strips 5 and 7 after their recesses have been stamped therein may be in the order of less than $\frac{1}{32}$ of an inch. Housing 3 of the completely assembled switch 1 thus has the appearance of a wafer-thin or pill-shaped watchcase having a depth of less than $\frac{1}{16}$ of an inch.

In FIG. 7, I have illustrated my improved thermally responsive switch 1 as it might be positioned between the main and start windings 45 and 47 of a motor which it is to protect from thermal overload. Its wafer-like configuration allows it to fit in between the curvature of these windings, and the start winding 47 replaces the function of the conventional bimetal heater. Conductive strips 5 and 7 provide a low resistance path for the flow of current through the switch, whereby there is very little internal heating of the strips and the switch by the current passing therethrough. The placement of the motor protector in the motor may be part of the manufacturing process of the motor itself.

It will thus be seen that I have provided a diminutive, wafer-thin, compact switch which includes a very simple conductive pair of strips that form a switch housing having integral terminations and a very low thermal mass with high thermal conductivity. This switch has a very low internal heating characteristic and will provide a good temperature response under load conditions. Besides providing very low electrical resistance, the strips 5 and 7 also result in a switch of low thermal mass. Thus as heat is supplied to the switch from the external apparatus to be controlled, for example, the switch 1 will follow closely the ambient temperature of its environment in that apparatus. Such a switch is simple and relatively easy to manufacture, and as a consequence thereof may be produced inexpensively. The over-all flat shape of this switch lends itself to numerous applications where the size of the switch is an important consideration. For any of its applications, my pill-shaped switch, will, of course, be electrically insulated from its particular environment, and in the motor shown in FIG. 7, it is insulated from the windings by the insulation of the windings themselves and also by an insulating layer or casing of plastic 49 formed around the conductive housing. It will be obvious to those skilled in the art that any number of simple techniques for electrically insulating my switch may be used, while in no way substantially increasing the over-all size of the switch.

It should be realized that certain aspects of my invention may be incorporated efficiently and beneficially in various types of thermally responsive switches where switch size, switch cost, and/or efficient switch operation, are important considerations.

While in accordance with the patent statutes, I have described what at present is considered to be the preferred embodiment of my invention, it will be obvious to those skilled in the art that various changes and modifications may be made therein, without departing from my invention, and I therefore, aim in the following claims to cover

all such equivalent variations as fall within the true spirit and scope of this invention.

What I claim as new and desire to secure by Letters Patent of the United States is:

1. A thermally responsive snap acting electric switch comprising a housing of wafer-like configuration formed by a pair of relatively thin conductive strips, said strips each having a recess therein thereby to form a switch cavity, fixed contact means positioned on the inner surface of one of said strips within said cavity, a support secured to said housing between said strips and extending into said switch cavity, a snap acting disc supported in cantilever fashion by said support between a free inner end of said support and said housing and disposed in said cavity, said disc having a substantially annular configuration and constructed of bimetallic material, a movable contact means positioned on a free peripheral portion of said annular bimetal disc for cooperation with said fixed contact means, a screw in threaded engagement with one of said strips, extending through said annular disc, and acting upon the free inner end of said support for selectively varying a predetermined temperature at which said disc will actuate said switch contacts, first insulating means electrically separating said strips from each other, said first insulating means comprising a thin layer of bendable insulating material, a plurality of clamping tabs formed on the outer periphery of one of said strips, the other strip having a generally uninterrupted flange formed on the outer periphery thereof, said clamping tabs of the one strip being folded over against the flange of the other strip with doubled over folds of the bendable insulating material interposed between and clamped by the tabs of the one strip and the flange of the other strip, said strips being securely sandwiched together about said insulating layer by engagement of said tabs of said one strip with said flange of said other strip, thereby to form a wafer-thin switch of compact configuration, low thermal mass, and high thermal conductivity, and a second insulating means substantially surrounding the switch housing to insulate the switch from its external environment.

2. A thermally responsive snap acting electric switch comprising a housing of wafer-like configuration formed by a pair of relatively thin conductive strips, said strips each having a recess therein thereby to form a switch cavity, fixed contact means positioned on the inner surface of one of said strips within said cavity, an elongated support secured at one end thereof to said housing between strips and having a free inner end disposed in said switch cavity, a snap acting annular disc of bimetallic material supported in cantilever fashion within said switch cavity by attachment to said support between the ends thereof, a movable contact button positioned on a free peripheral portion of said annular bimetal disc for cooperation with said fixed contact means, a screw in threaded engagement with one of said strips, extending through said annular disc, and acting upon said free inner end of said support for calibrating the temperature at which said disc will actuate said switch contacts, first insulating means electrically separating said strips from each other, said first insulating means comprising a thin layer of bendable insulating material, a plurality of clamping tabs formed on the outer periphery of one of said strips, the other strip having a generally uninterrupted

ruptured flange formed on the outer periphery thereof, said clamping tabs of the one strip being folded over against the flange of the other strip with doubled over folds of the bendable insulating material interposed between and clamped by the tabs of the one strip and the flange of the other strip, said strips being securely sandwiched together about said insulating layer by engagement of said tabs of said one strip with said flange of said other strip, thereby to form a wafer-thin switch of compact configuration, low thermal mass, and high thermal conductivity, and a second insulating means substantially surrounding the switch housing to insulate the switch from its external environment.

3. A thermally responsive snap acting electric switch comprising a housing of wafer-like configuration formed by a pair of relatively thin conductive strips, said strips each having a recess therein thereby to form a switch cavity, each of said strips having a terminal portion integral thereto, fixed contact means positioned on the inner surface of one of said strips within said cavity, an elongated support of rigid material secured at one of its ends to said housing between said strips and having an inner free end disposed in the approximate center of said switch cavity, a snap acting annular disc of bimetallic material supported in cantilever fashion within said switch cavity by attachment to said support between the ends thereof, a movable contact button positioned on a free peripheral portion of said annular bimetal disc for cooperation with said fixed contact means, a screw in threaded engagement with one of said strips, extending through said annular disc, and acting upon said free inner end of said support for moving said disc and selectively varying a predetermined temperature at which said disc will actuate said switch contacts, first insulating means electrically separating said strips from each other, said first insulating means comprising a thin layer of bendable insulating material, a plurality of clamping tabs protruding outwardly from the outer periphery of one of said strips, the other strip having a generally uninterrupted flange formed on the outer periphery thereof, said clamping tabs of the one strip being folded over against the flange of the other strip with doubled over folds of the bendable insulating material interposed between and clamped by the folded over tabs of the one strip and the flange of the other strip, said strips being securely sandwiched together about said insulating layer by engagement of said tabs of said one strip with said flange of said other strip, thereby to form a wafer-thin switch of compact configuration, low thermal mass, and high thermal conductivity, and a second insulating means substantially surrounding the switch housing to insulate the switch from its external environment.
